TUBE FRAME

Filed Dec. 3, 1925

UNITED STATES PATENT OFFICE.

EDGAR F. HATHAWAY, OF WELLESLEY, AND CHARLES LEA, OF MILTON, MASSACHUSETTS, ASSIGNORS TO SHAWMUT ENGINEERING COMPANY, OF BOSTON, MASSACHUSETTS, A CORPORATION OF MASSACHUSETTS.

TUBE FRAME.

Application filed December 3, 1925. Serial No. 72,997.

This invention relates to tube frames and is intended to provide a light, inexpensive and rigid structure particularly adapted for use on narrow looms for weaving Axminster carpets.

At the present time tube frames for weaving wide seamless rugs are preferably made with tubular metallic carrier-bars in preference to carrier-bars of wood because of the greater stiffness and rigidity and durability, as well as the lighter weight as compared with a wooden bar with its metal re-enforcements. In the field of narrow fabric Axminster looms, however, the wooden carrier-bars have continued in use because tube-frames of short length would not require such re-enforcement as the long tube-frames required, and it was possible to make them of wood lighter and cheaper than if they were made of drawn seamless tubing.

The present improvements, while applicable to other types of tube-frames, are particularly intended to provide a construction which can be made sufficiently light to fit it for service on narrow tube-frames, and which can be made so cheaply as to successfully compete with the short wooden carrier-bars heretofore in use, and that too without sacrificing the stiffness or resistance to torsional or twisting strains.

With these objects in view the invention comprises an improvement in the carrier-bar itself by which a light, cheap and stiff carrier-bar can be readily produced from sheet metal; second, in the construction and arrangement of the tube-frame hangers or brackets by which the tube-frames are suspended from their carrier-chains and afford rotatable support for the yarn-delivering spools.

These and other features of the invention will be particularly described in the following specification and will be defined in the claims hereto annexed.

In the accompanying drawings we have illustrated a preferred form embodying the principles of this invention, in which:

Figure 1 is a front elevation of the complete tube-frame, the middle portion of which is broken away.

Figure 2 is an inside elevation of one of the brackets and hangers attached to the carrier-bar, the latter being shown in cross-section.

55

Figure 3 is a front elevation, partly in central section, of one of the hangers before attachment to the carrier-bar.

Figure 4 is an outside end elevation of the tube-frame without the spool and without the tuft-tubes.

60

Figure 5 is a detail showing in cross-section the manner in which the hollow carrier-bar is held by the tuft-tubes under tension.

65

Figure 6 is a perspective view of a portion of the carrier-bar having an inserted wooden core with some of the tuft-tubes secured in operative position thereon.

70

In the practice of this invention, as illustrated in the drawings, the longitudinal carrier-bar is formed in a properly dimensioned longitudinal strip of sheet metal of a comparatively thin gauge which is folded into tubular form so as to form top, back 75 and bottom walls, a longitudinal gap being left in front between the longitudinal edges of the sheet metal, which gap is bridged over by the row of tuft-tubes as will now be described.

80

In folding the hollow bar or tube 1, the bottom wall 1^b, is extended forwardly of the main body of the tube and is formed with a series of transverse notches or apertures, as shown at 2, for the reception of the tuft-tubes. The forward edge of the top-wall is bent down to form a convex or over-hanging longitudinal rib 1^c, near the edge, while the edge portion 1^a lies in a flat direction to form a backing for the intake ends of 90 the row of tuft-tubes t. The tuft-tubes t are in the form of hollow flat tapered tubes of usual construction except that their back-walls are struck out to form a small spring-tongue t', located at a predetermined distance from the intake end thereof so that when each tuft-tube is crowded through to the tuft-tube receiving aperture 2 in the projecting ledge 1^b, of the carrier-bar, the tongue t' is momentarily compressed and 95 then, upon being forced through the ledge, springs out, as shown in Figure 5, to form

95

100

a shoulder or lock preventing its withdrawal until the locking tongue is sprung inward.

When the tubes have thus been inserted 5 the top and bottom walls are pressed toward each other and held in contracted position until the intake ends of the tuft-tubes are soldered to the supporting face of the ledge 1^a. The solder can be readily applied to 10 the end edges of the back-walls because the over-hanging or projecting rib 1^c prevents the tuft-yarn from coming in contact with the solder distributed along beneath such rib.

15 After the soldering operation the tuft-tube is released from the compression against the top and bottom walls but the opposite longitudinal edges of the strip are held under strong tension by the bridging 20 action of the tuft-tubes themselves which are anchored to the bottom wall by their tongues *t'*, and are soldered to the supporting front face 1^a, as previously described. The object of placing the tubular carrier-bar under tension is to gain increased stiffness in the structure so as to resist not only sagging in the middle but, more particularly, to resist the torsion or twist which is likely to be encountered where a very thin 25 gauge of metal is used for the carrier-bar.

This torque-resisting effect may be increased by the insertion of a wooden core or internal-bar 3, and when this is used the compression of the top and bottom walls 30 against the wooden core, before soldering the tuft-tubes in place, serves a double purpose. Not only does it assist in stiffening the bar against torque, but it also serves as a means of holding the wooden core 3 against 35 displacement. Since the wooden core is used only as a torque-resisting feeler it need not extend the whole length of the bar, and what is more important it may be made of soft, light wood, such as white pine, which 40 is very easily compressed and is very light in weight. The further object in compressing and contracting the metal bar on such a core is that it maintains firm contact between the metal bar and the wooden core 45 50 in spite of slight shrinkages and, therefore, utilizes at all times the torque-resisting effect of the wooden core undiminished by shrinkage.

The end brackets used for suspending the 55 carrier-bar from the carrier chains are, generally speaking, alike except in one particular. The suspension bracket at one end of the bar has a closed bearing for the spool, while the suspension bracket at the other 60 end has an open bearing for the spool-journal so that the journal can be lifted out of the open end-bearing and then drawn endwise out of the closed end-bearing. A movable keeper or retaining latch is used in the 65 open bearing, as will now be explained.

In each case the bearing bracket comprises a vertical arm 4, to whose lower portion there is secured an attaching member 5 which, in this case, is in the form of a three-sided or U-shaped clip whose free ends are 70 formed with tenons 5, 5^a, inserted in corresponding apertures formed in the lower portion of the hanger or arm, these tenons being secured in place by heading down the outer end, or in any suitable manner. The 75 tenon 5, at the lower portion of the attaching bracket, is struck up from the middle portion of the lower horizontal arm forming, so to speak, a tongue between two fork-like members 5^c, whose ends abut 80 against the inner face of the arm 4.

At the lower end of each bracket there is formed a fulcral aperture 4^a to receive the open eye or loop 6^a of the suspension latch-hook 6, whose upper end terminates in the chain-engaging hook 6^b. A fulcral pin 7, inserted through the open eye at the bottom end of the latch 6, after the latch has been inserted in its fulcral aperture 4^a, serves to pivotally support the latch, and when the bracket is placed inside the tubular carrier-bar the pin is prevented by the front and rear walls from accidental displacement.

The upper portion of the brackets 4 is divided into two branches, the outer branch 4^b, forming a chain-penetrating arm outwardly offset and upwardly extending to pass into the link of a supporting chain, while the inner branch 4^c forms a bearing member for supporting the journal 10^a of 100 the yarn-spool 10, as shown at the left of figure 1. The spool-bearing member 4^d of the right-hand bracket, as shown in Figure 1, instead of having a closed bearing has an open or notched bearing, as shown in 105 Figures 2 and 3 and we, therefore provide a keeper or journal-retaining latch 8 to prevent accidental displacement. This spool-latch 8 is bent at its lower end to form an angular depression, as shown at 8^a, which 110 is adapted to seat itself in a fulcral aperture 4^e, formed in the suspension arm 4 a little distance above the top of the carrier-bar. This offset or recessed portion of the latch affords both a fulcral portion for the support of the latch in the fulcral recess and also affords a recess or seat for the spring 9, which is interposed between a depression 6^b of the suspension latch 6, so 115 that the spring exerts a thrust in opposite directions against both of these latches while the latches afford support for the spring. The spool-latch, near its upper end, has its interior portion struck out to form a lateral lip 8^b which normally projects into the open bearing recess 4^a, in the suspension hanger and prevents the escape of the spool-journal therefrom. When it is desired to remove the spool from the tube-frame the spool-latch 8 is pressed outward against the ten- 120 125 130

sion of the spring 9, as shown in Figure 3, making it possible to leave the adjacent spool journal out of its bearing and withdraw the opposite spool-journal endwise 5 from the closed bearing at 4°.

The construction of the hangers with their attaching member is so rigid that they can be made of comparatively light pressed metal stock and, furthermore, the parts of 10 the suspension hanger are so constructed and arranged as to be very easily and quickly assembled or removed. The attaching member 5, when inserted in the end of the tubular bar, is rigidly secured therein by opposite 15 screws 15. The device, therefore, affords at the same time a very light and a very rigid construction, all the parts of which can be made from pressed steel and are, therefore, 20 very inexpensive so that both in lightness and in economy the device compares favorably with the wooden carrier-bar construction heretofore used on narrow tube-frames, while possessing in a high degree rigidity 25 and resistance against torsional or twisting strains.

It will also be noticed that both the spool-latch and the chain-engaging latch are inserted through the slot in the offset portion 29 of the arm 4 formed by striking out from the interior of its upper portion the spool-bearing member 4^a. In this way the aperture in the upper portion of the arm forms a guiding journal or slot preventing side- 35 wise displacement of both these latches and insuring the maintenance of the latches in their correct operative positions for service.

What we claim is:

1. In a tube-frame the combination of a 40 carrier-bar comprising a longitudinal strip of sheet metal bent lengthwise to form a tubular bar open along its front, the bottom wall being extended forward to form an apertured ledge for receiving a row of tuft tubes, the upper portion of the front being bowed out and projected downward to form 45 a tuft-tube attaching face, and a row of tuft-tubes inserted through the apertures in said ledge with their intake ends soldered to the front face while the bar is contracted vertically by compression whereby the tubes 50 form means for connecting the two edges of the folded bar and maintaining it under tension.

2. In a tube-frame the combination of a 55 carrier-bar embracing a longitudinal strip of sheet metal folded into tubular form to leave a longitudinal gap between its edges along the front thereof, the bottom wall being projected forward to form a projecting ledge having transverse tube-receiving apertures, a torque-resisting stiffening core 60 inserted inside said bar and held therein by contractile tension of the bar, a row of tuft-tubes secured to the opposite edge portions 65 of the bar to bridge across the gap in its

front and maintain the contractile tension of the bar upon its core, substantially as described.

3. A suspension bracket for a tube-frame embracing in its construction a suspension 70 arm, a spring hook-latch mounted thereon to releasably engage a carrier-chain, a bar-attaching member comprising a substantially U-shaped piece formed to be inserted in the open hollow end of a carrier-bar, the 75 opposite end portions of said attaching member being formed with projecting tenons extending through apertures in the corresponding portions of the hanger and being firmly secured therein.

4. A suspension bracket for a tube frame provided at its lower end with means for securing it firmly to the hollow end portions of a carrier-bar, said bracket being formed with fulcral apertures in its lower and in 80 its middle portions one above the other, a chain-engaging hook-latch fulcrumed in the lower aperture and a spool journal-retaining latch fulcrumed in the other, both latches being pressed into normal operative position 85 for service by an interposed oppositely thrusting spring.

5. An end bracket for a tube-frame embracing in its construction, a vertical arm adapted to be secured to the carrier-bar of 90 a tube-frame and having at its upper end chain-penetrating and spool-bearing members, the spool-bearing member being provided with an open bearing recess for the 95 spool-journal, a journal-retaining latch 100 loosely seated in a recess formed in the middle portion of said arm to swing in the longitudinal plane of the tube-frame and being formed at its upper end to overhang the spool-journal when pressed into normal 105 operative position while being movable outward to allow the journal to be lifted from its bearing.

6. An end bracket for a tube-frame embracing an arm adapted to be secured to the 110 end of a tube-frame carrier-bar, said arm having the interior part of its upper portion struck out and inwardly offset from the remaining portion of the upper end to form a spool-bearing member with an open bearing recess thereby leaving an interior 115 aperture in said arm, a spool-latch and a chain-engaging latch each projecting through said aperture and fulcrumed in the arm below said aperture and normally held under spring tension in normal operative 120 position.

7. An end bracket for a tube-frame embracing a vertical arm adapted to be secured to the carrier-bar of a tube-frame, the upper portion of which is formed with two 125 projecting relatively offset members of unequal length, the inner struck out from the interior portion of the outer member and forming an open bearing for a spool-journal, 130

11
21
opposing latches fulcrumed in lower portions of the arm and projecting upwardly through an aperture in its offset upper portion, a thrust-spring interposed between said latches to thrust them yieldingly apart, the inner latch normally overhanging the adjacent spool-bearing and the outer one being yieldingly held in position to overhang a carrier-chain.

- 10 8. An end bracket for a tube-frame embracing a suspension arm provided with means for rigidly securing it to the carrier-bar of a tube-frame, and formed with two upwardly extending offset extensions, the inner one being provided with an open bearing for a yarn spool, the outer one forming a chain-penetrating member, a spool-retaining latch whose lower end is formed with an offset fulcral portion adapted to be seated 15 in an aperture in said arm, a suspension latch fulcrumed in the arm below the fulcral point of the spool latch, a thrust-spring interposed between said latches and supported by them, both latches passing through an aperture in the offset portion of the arm and being guided thereby in their movements to and from operative position.
- 20 25 9. An end bracket for a tube-frame embracing an arm provided at its lower end

with means for attaching it rigidly to the 30 carrier-bar of a tube-frame, a chain-engaging hook-latch attached to said arm, a spool-bearing member disposed inwardly in relation to said hook-latch and provided with an open bearing recess, a spool-latch whose 35 lower portion is inwardly depressed to form a fulcral portion adapted to seat in a receiving aperture formed in said arm and to receive an exterior thrust spring arranged to 40 press the spool-latch inwardly until the upper end of the latch overhangs the said open bearing for the spool.

10. An end bracket for a tube-frame, embracing a suspension arm, a three-sided attaching member secured to its lower end 45 by tenons inserted and secured in apertures formed in said arm by heading down the outer ends of said tenons, the attaching member forming in conjunction with the adjacent portion of the arm, a hollow four-sided attaching member fitting into the hollow end portion of a carrier-bar adapted to receive fastening screws passed through opposite walls of the carrier-bar.

In witness whereof, we have subscribed 50
the above specifications.
